UNITED STATES PATENT OFFICE.

CORBON L. HARVEY, OF ST. LOUIS, MISSOURI.

LOOSE-LEAF BINDER.

1,385,745.

Specification of Letters Patent. Patented July 26, 1921.

Application filed July 19, 1920. Serial No. 397,412.

To all whom it may concern:

Be it known that I, CORBON L. HARVEY, a citizen of the United States, residing at St. Louis, Missouri, have invented a certain new and useful Improvement in Loose-Leaf Binders, of which the following is a full, clear, and exact description, such as will enable others skilled in the art to which it appertains to make and use the same, reference being had to the accompanying drawings, forming part of this specification, in which—

Figure 1 is a plan view of my improved loose leaf binder.

Fig. 2 is an enlarged vertical sectional view on the line 2—2 of Fig. 1.

Fig. 3 is a plan view of the locking bar.

Fig. 4 is an enlarged cross-sectional view on the line 4—4 of Fig. 3.

Fig. 5 is a detail view of parts of the extensible post.

Fig. 6 is a detail view of the cam member which moves the locking bar.

Fig. 7 is a detail view showing my extensible post used in connection with a supplemental post section.

This invention relates to a new and useful improvement in loose-leaf binders, the object being to construct a binder of the character described which will be cheap, easily operated, and effective, particularly when employed in connection with an improved form of rack, forming the subject-matter of a companion application filed by me of even date herewith.

In the drawings, 1 indicates the top cover, to which is hingedly connected a split or divided back frame bar 2. This bar 2 is composed of two sections 3 and 4 connected together by screws 5, the former section having a longitudinally disposed groove in its lower face in which locking bar 6 is slidably arranged. Bar 6 is formed with a keyhole opening 6^a at each end, and at about its center is provided with a transversely disposed slot 6^b. 7 indicates a disk seated in a socket in section 3 (above the bar 6) and having a crank-pin 8 operating in the slot 6^b, whereby upon a half turn being imparted to the disk, the locking bar is moved longitudinally a distance equal to the throw of the crank pin, the position of the bar at the left, as shown in Figs. 2 and 3, being its locked position (wherein the narrow portions of the keyhole openings engage under the heads of the posts, hereinafter de-

scribed) while the position of the bar at the right is its unlocking (or unlocked) position, wherein the enlarged portions of the keyhole openings register with the heads of the posts, 60 and permit the top cover to be removed as an entirety.

The crank disk 7 is provided with a squared stud 9 to receive a key which may be introduced through the opening 3^a in the plate 3, 65 whereby said crank disk may be operated.

10 indicates the sleeve portion of an extensible post having a reduced annulus 10^a forming a head portion 10^b, under which the edge of the keyhole openings is moved when 70 the locking bar is operated to lock the top cover in position, as shown in Fig. 2.

10^c indicates an inwardly extending flange forming a bearing near the upper end of the sleeve 10, which bearing provides a support 75 for the head of a threaded rod 11 whose upper end is squared, as at 11^a, to receive a key through an opening 3^b in the plate 3 by which the rod 11 may be rotated. In order to hold the rod 11 in position against 80 the bearing 10^c, I introduce a washer 12 through the upper end of the bore of the sleeve, and by a driving fit force the same down close to the head portion of the threaded rod 11, whereby said rod may be freely 85 rotated but is prevented from longitudinal displacement relative to the sleeve.

13 indicates a female member of the extensible post having an opening to receive the rod 11, said post 13 fitting snugly within 90 the sleeve 10, but permitting freedom of movement of sleeve 10 thereon. The lower end of post 13 is provided with a non-circular shank portion 13^b below which is a head portion 13^c. 13^d indicates a nut having a 95 threaded opening for co-operating with the rod 11, and which nut is provided with a threaded stem screwed into the upper end of post 13. When it is desired to introduce a supplemental post section 13^a in position 100 to extend the post beyond the limits of the adjustment of the rod 11, this nut 13^c is removed from the upper end of post 13. The extra post section 13^a is then screwed into the top of post 13, and finally the nut 13^c 105 is screwed into the upper end of the supplemental post section 13^a, as shown in Fig. 7. This method of extending or building up posts, I believe, is well known in the art.

14 indicates a screw whose head portion 110 is accessible from the exterior, and which screw, when turned in against the non-cir-

cular shank 13^a locks the post 13 in position and at the same time prevents rotation thereof. When the screw 14 is turned out sufficiently far, the post 13 and its associated parts may be entirely removed. When the post 13 is locked in position in the bar 15, which constitutes the lower backing plate to which the lower cover 16 is hingedly connected, as shown in Fig. 1, the rotation of the threaded rod 11, say, in an anticlockwise direction, will cause the sleeve 10 to be raised relative to the post 13, thus extending the post and permitting introduction of new leaves into the volume. These leaves are indicated by dotted lines 17 in Fig. 1 and have notches 17^a at their four corners by which they engage the extensible post, these notches permitting the leaves to be inserted and removed at will into and from any portion of the volume without necessitating the removal or displacement of the other leaves, except, of course, to offer sufficient space for the introduction of a new leaf or sufficient clearance for the removal of an old leaf.

25 There are two extensible posts connecting the backing plates of the cover, and both of these posts are preferably of similar construction and interchangeable, being removably mounted in the bottom backing plate as above described. I shall not describe in detail the second extensible post, indicated at 18 as an entirety, as the same, as just stated, may be similar in construction to the extensible and removable post hereinbefore described.

What I claim is:

1. A loose leaf binder consisting of two

backing plates, a removable post composed of telescoping sections, one of which is mounted in one of said backing plates, said section at its point of mounting in said plate having a non-circular shank portion and a head, and a set screw in the backing plate for engaging said non-circular shank portion. 40

45 2. A loose leaf binder consisting of two backing plates, an extensible post comprising telescopic sections, one of which is seated in one of said backing plates, a set-screw for holding said post-section in position, on said plate, a locking bar on the other of said backing plates for engaging a head on the other of said post sections, said two-post sections being connected together by a rod having threaded engagement with one of said post-sections, and a rotatable engagement with the other. 50

3. A loose leaf binder consisting of two backing plates, one of which has a seat, a post section in said seat, means for locking said post section in its seat, said post section being tubular at one end, a nut secured in said tubular end, a telescoping complementary post section having a head on its outer end, means on the other of said backing plates for engaging said head, and a threaded rod mounted for rotation in the last mentioned post section, said rod engaging said nut, and means for holding said rod against longitudinal movement relative to the post section in which it is mounted. 60

65 In testimony whereof I hereunto affix my signature this 12th day of July, 1920.
CORBON L. HARVEY.
